BRÜDER HARDY, MASCHINENFABRIK UND GIESSEREI AKTIEN GESELLSCHAFT, OF
VIENNA, AUSTRIA.

AIR-PRESSURE BRAKE.

Application filed November 28, 1927, Serial No. 236,327, and in Austria December 15, 1928.

This invention relates to an air pressure brake of that class in which two pistons differing in diameter and moving in opposite directions act in succession on the link and lever gearing of the brakes, the smaller piston acting first being locked in position at the end of its stroke by a pawl and ratchet gear. According to the invention this pawl and ratchet gear is located in the casing between the two pistons. Thereby not only a very compact structure is secured and more particularly the result is obtained that all the parts of the pawl and ratchet gear are protected from injury and dust as also from snow and ice by the casing surrounding the same.

The drawings illustrate by way of example a constructional form of the invention. Figs. 1 to 3 show the apparatus in the position of release, of a contact and fully applied position. Fig. 4 shows a detail. Figs. 5 and 6 show another constructional form and Fig. 7 illustrates a further constructional form of the brake.

In the closed casing 1 secured to the vehicle frame two coaxial brake cylinders 38, 39 differing in diameter are provided in which work the pistons 2 and 3. The hollow piston rod 40 of the piston 2 secured to and preferably made integral with the same carries at its end projecting from the cylinder an elongated slot 41 into which engages a journal pin 15 of the link and lever gear of the brake. An abutment 42 on the casing 1 serves for holding this journal pin in the release position of the piston 2. The connection of the small piston 3 with the link and lever gear is effected by an eye 44 provided in its piston rod 43 into which eye engages the bolt 20 of the link and lever gearing.

The link and lever gearing of the brake consists of the levers 16 and 21 carrying the bolts 15 and 20 to which levers are pivoted at 17 and 22, the operating links 19 and 24 of the brake shoes being suspended at 45 on the vehicle frame.

The levers 16 and 21 are connected by a link 25 pivoted to these levers by bolts 26, 27 and by a retracting spring 28 tending to return the levers into the release position.

Each of the pistons 2 and 3 is acted upon by a spring 4 and 6 respectively. In the case of the constructional form shown in Figs. 1 to 3 to the large piston a strong

spring 4 and to the small piston a weaker 55 spring 6 is associated.

Air under pressure enters through any suitable or preferred control valve 29 and the channel 30 into the working space of the cylinder 39 connected to the working space of the cylinder 38 by a passage 47 including a three way cock 12.

The piston 3 carries with some slight axial play a ratchet rack 7 guided in the casing 1 the free end of such rack reaching into a tubular extension 46 fixed in the casing and projecting into the hollow piston rod 40 of the piston 2. A pawl 8 pivoted at 9 in the casing 1 and acted upon by a spring 10 is adapted to engage with this ratchet rack. 70 The pawl 8 is held in its disengaged position by a pin 11 acting on an arm of the pawl and guided in a bore in the casing by a shoulder or piston 18 mounted thereon and tightly fitting such bore the said pin abutting against the piston 2. The shoulder of the pin might also be replaced by a diaphragm. The by passages 13 and 14 serve for equalizing the pressures on both sides of the pistons while in the release position. 75

Fig. 1 shows the apparatus in the release position. When the brakes have to be applied air under pressure is admitted through the control valve 29 and the passage 30 on the front side of the piston 3 moving it to the right together with the rack 7 against the action of the spring 6 and the resistances of the link and lever gear. Furthermore air under pressure enters through the passage 47 and the cock 12 at the front side 80 of the piston 2. This piston which at one side is constructed in the manner of a valve and the cylinder head opposite thereto carry circular ribs 5 which tightly fit each other as long as the brakes are released, so that the 85 air under pressure first acts only on part of the piston surface and cannot move the piston against the action of the strong spring 4. The bolt 15 therefore constitutes a stationary fulcrum for the link and lever gear 100 of the brake, which owing to the movement of the piston 3 is brought into the position shown in Fig. 2 in which the brake shoes 23 are in contact with the wheel tyres.

In the meanwhile the pressure of the air 105 entering the cylinder 39 and hence also acting on the central part of the piston gradually increases until finally its pressure ex-

ertered on the front side of the piston 2 has increased so far that now the resistance of the spring 4 is overcome and the piston is moved to the left. Owing to the fact that when the ribs 5 come out of contact with each other at this moment the pressure begins to act on the entire surface of the piston and the brake shoes 23 as pressed against the wheels with great force as shown in Fig. 3.

When the piston moves away from its release position it releases the pin 11 and hence also the pawl 8 which latter then engages into the ratchet rack and thereby locks the piston 3 in its position. Therefore during the stroke of the piston 2 the bolt 20 engaging the piston rod 43 forms the fixed fulcrum of the link and lever gears. The slight lost motion between the rack 7 and the piston 3 secures the engagement of the pawl 8 into the rack 7.

When the brake shoes have to be released the air under pressure is permitted to escape from the working chambers of the cylinders 38 and 39 by the control valve 29, so that the piston 3 being locked in position by the pawl 8, first the piston 2 returns under the action of the spring 4 and the elastic forces of the deformed link and lever gear. On reaching its initial position it pushes the pin 11 to the right and thereby disengages the pawl 8 so that then the piston 3 is pushed back by the spring 6, until the parts have resumed their positions shown in Fig. 1.

If the three way cock 12, establishing communication between the working spaces of the cylinders 38 and 39, is in the position shown in Fig. 4 it shuts off the admission of air under pressure to the piston 2 and connects its working chamber with the atmosphere through the port 31. In this case the brakes are applied only by the small piston 3. This expedient will be made use of in the case of freight trains which when empty require only a small brake force for the obtention of which the small piston is sufficient. If the vehicles are loaded the cock is turned again into the position shown in Fig. 1 and the brakes are applied in the manner above described.

The same arrangement may be used for brakes for express trains the cock being adjusted according to the running speed. In this case the cock may be operated automatically by any one of the well known brake force governors dependent on the speed.

In the constructional form shown in Fig. 5 the operative surface of the large piston 2 is made smooth and a special loaded valve is interposed in the connecting channel 47 of the cylinders 38 and 39. The valve body 32 guided in the casing 1 is movable between two seals 34 and 36 and is acted upon by a spring 33 tending to force it against the seat 34. In the position shown in Fig. 5 the admission of air under pressure to the cylinder 38 is shut off and the space in front of the piston 2 is connected to the atmosphere by the port 35. When during the movement of the brake shoes towards the wheels due to the movement of the piston 3 as above described, the pressure in the channel 47 has sufficiently increased to overcome the resistance of the spring 33, the valve body 32 is moved into the position shown in Fig. 6 in which it opens the admission of air under pressure to the piston 2 which then operates as described.

According to Fig. 7 the valve 32 is located in the control valve 37 itself controlling in this case two channels. By one of these channels and the channel 30 air under pressure enters on operating the control valve immediately in front of the piston 3 while the second channel 48 is opened after the pressure has increased to a certain degree and hence after a time sufficient for the small piston 3 to bring the brake shoes into contact with the wheels.

Finally it is observed that instead of the pawl and ratchet gear also a self arresting frictional escapement gear may be used.

What I claim is:

1. In an air pressure brake comprising a casing, two coaxial cylinders, arranged opposite each other in such casing and differing in diameter, pistons, one for each cylinder, working in such cylinders and adapted to move in opposite directions, piston rods connected to such pistons, springs arranged and adapted to act on the sides remotest from each other, means for supplying air under pressure to the ends of the cylinders next to each other, a locking device comprising a ratchet element connected to the smaller piston and a pawl element pivoted in the said casing and adapted to engage into the said ratchet element and means for actuating the said pawl element, the said locking device being arranged between the two pistons.
2. In an air pressure brake comprising a casing, two coaxial cylinders arranged opposite each other in such casing and differing in diameter, pistons, one for each cylinder, working in such cylinders and adapted to move in opposite directions, a hollow piston rod for the larger cylinder and a piston rod for the smaller cylinder, springs arranged and adapted to act on the sides remotest from each other, means for supplying air under pressure to the ends of the cylinders next to each other, a tubular extension in the casing projecting into the hollow piston rod of the larger cylinder, a pawl and ratchet gear comprising a ratchet rack connected to the smaller piston and guided in the said tubular extension of the casing and a pawl pivoted in the said casing and adapted to engage into the said ratchet rack and means for actuating the said pawl.
3. In an air pressure brake comprising a

casing, two coaxial cylinders, arranged opposite each other in such casing and differing in diameter, pistons, one for each cylinder, working in such cylinders and adapted to move in opposite directions, piston rods connected to such pistons, springs arranged and adapted to act on the sides remotest from each other, the spring of the larger piston being stronger than that of the smaller piston 10 ton, means for supplying air under pressure to the ends of the cylinders next to each other, a pawl and ratchet gear comprising a ratchet rack connected to the smaller piston and a pawl pivoted in the said casing and 15 adapted to engage into the said ratchet rack and means for actuating the said pawl, the said pawl and ratchet gear being arranged between the two pistons.

4. In an air pressure brake comprising a 20 casing, two coaxial cylinders, arranged opposite each other in such casing and differing in diameter, pistons, one for each cylinder, working in such cylinders and adapted to move in opposite directions, piston rods connected to such pistons, springs arranged and 25 adapted to act on the sides remotest from each other, means for supplying air under pressure to the ends of the cylinders next to each other, a pawl and ratchet gear comprising a ratchet rack connected to the smaller piston and a pawl pivoted in the 30 said casing and adapted to engage into the said ratchet rack and means operatively connected to the larger piston for bringing the 35 said pawl into engagement with the ratchet rack whenever the larger piston moves away from the smaller piston, the said pawl and ratchet gear being arranged between the two pistons.

40 5. In an air pressure brake comprising a casing, two coaxial cylinders, arranged opposite each other in such casing and differing in diameter, pistons, one for each cylinder, working in such cylinders and adapted to move in opposite directions, piston rods connected to such pistons, springs arranged and 45 adapted to act on the sides remotest from each other, means for supplying air under pressure to the ends of the cylinders next to each other, a pawl and ratchet gear comprising a ratchet rack connected to the smaller piston and a pawl pivoted in the 50 said casing and adapted to engage into the said ratchet rack and a link and lever gearing operatively connected to the larger piston and a 55 load acting on the pawl whereby the pawl engages into the ratchet rack whenever the larger piston moves away from the smaller piston and at other times is disengaged 60 from the ratchet rack, the said pawl and ratchet gear being arranged between the two pistons.

65 6. In an air pressure brake comprising a casing, two coaxial cylinders, arranged opposite each other in such casing and differing

in diameter, pistons, one for each cylinder, working in such cylinders and adapted to move in opposite directions, piston rods connected to such pistons, springs arranged and adapted to act on the sides remotest from each other, means for supplying air under pressure to the ends of the cylinders next to each other, such means comprising a shutting off element adapted to shut off the supply of air under pressure to the larger piston, a locking device comprising a ratchet element connected to the smaller piston and a pawl element pivoted in the said casing and adapted to engage into the said ratchet element and means for actuating the said pawl element, the said locking device being arranged between the two pistons.

7. In an air pressure brake comprising a 70 casing, two coaxial cylinders, arranged opposite each other in such casing and differing in diameter, pistons, one for each cylinder, working in such cylinders and adapted to move in opposite directions, piston rods connected to such pistons, springs arranged and adapted to act on the sides remotest 75 from each other, means for supplying air under pressure to the ends of the cylinders next to each other, such means comprising a shutting off element adapted to shut off the supply of air under pressure to the larger piston, a locking device comprising a ratchet element connected to the smaller piston and a pawl element pivoted in the said casing and adapted to engage into the said ratchet element and means for actuating the said pawl element, the said locking device being arranged between the two pistons.

8. In an air pressure brake comprising a 80 casing, two coaxial cylinders, arranged opposite each other in such casing and differing in diameter, pistons, one for each cylinder, working in such cylinders and adapted to move in opposite directions, piston rods connected to such pistons, springs arranged and adapted to act on the sides remotest 85 from each other, means for supplying air under pressure to the ends of the cylinders next to each other, such means comprising a shutting off element adapted to shut off the supply of air under pressure to the larger piston, and means for simultaneously connecting the pressure space of the larger cylinder to the atmosphere, a locking device comprising a ratchet element connected to the smaller piston and a pawl element pivoted in the said casing and adapted to engage into the said ratchet element and means for actuating the said pawl element, the said locking device being arranged between the two pistons.

9. In an air pressure brake comprising a 90 casing, two coaxial cylinders, arranged opposite each other in such casing and differing in diameter, pistons, one for each cylinder, working in such cylinders and adapted to move in opposite directions, piston rods connected to such pistons, springs arranged and adapted to act on the sides remotest 95 from each other, means for supplying air under pressure to the ends of the cylinders next to each other, such means comprising a shutting off element adapted to shut off the supply of air under pressure to the larger piston, and means for simultaneously connecting the pressure space of the larger cylinder to the atmosphere, a locking device comprising a ratchet element connected to the smaller piston and a pawl element pivoted in the said casing and adapted to engage into the said ratchet element and means for actuating the said pawl element, the said locking device being arranged between the two pistons.

10. In an air pressure brake comprising a 100 casing, two coaxial cylinders, arranged opposite each other in such casing and differing in diameter, pistons, one for each cylinder, working in such cylinders and adapted to move in opposite directions, piston rods connected to such pistons, springs arranged and adapted to act on the sides remotest 105 from each other, means for supplying air under pressure to the ends of the cylinders next to each other, such means comprising a bore in the casing, a pawl and ratchet gear comprising a ratchet rack connected to the smaller piston and a pawl pivoted in the

110 said casing and adapted to engage into the said ratchet rack and means for actuating the said pawl, such means comprising a pin adapted to reciprocate longitudinally in the said bore and an element adapted to move with the said pin and to tightly close the 115 said bore, the said pawl and ratchet gear being arranged between the two pistons.

120 125 In testimony whereof I have affixed my signature.

EMIL KREHANN.
